UNITED STATES PATENT OFFICE.

HARRY BLAND STRANGE, OF DORE, ENGLAND, ASSIGNOR TO MESSRS. THOMAS FIRTH & SONS LIMITED, OF SHEFFIELD, ENGLAND.

PERCUSSION-FUSE FOR PROJECTILES.

972,034.

Specification of Letters Patent.

Patented Oct. 4, 1910.

Application filed July 7, 1910. Serial No. 570,853.

To all whom it may concern:

Be it known that I, HARRY BLAND STRANGE, a subject of the King of England, residing at Dore, Derby, in England, have invented certain new and useful Improvements in Percussion-Fuses for Projectiles, of which the following is a specification.

This invention relates to percussion fuses of the type in which there is a plate or diaphragm which must be perforated by a punch carried by a sliding hammer which is driven forward on the impact of the projectile before the flash can be communicated from the detonator to the projectile charge. According to this invention the needle-carrying pellet so disposed within the fuse body as to be capable of sliding therein, has mounted upon it, preferably rigidly, one or more punches or the like which serve both to hold the pellet in its normal inoperative position and also to perforate the safety disk and allow the pellet to be operative the arrangement being such that the pellet can only move forward with the punches and is positively prevented from such forward motion until perforation has taken place. The safety disk is so disposed as to effectively close one or more passages through which alone the flash can be communicated from the detonator to the projectile charge, these passages acting as guides for the punches which are so constructed, as for instance by being formed hollow or otherwise, as to allow the flash to pass after the punches have perforated the disk. The punches maintain the pellet in its inoperative position by reason of their ends bearing on the face of the disk which being preferably formed of substantial thickness insures the pellet being maintained inoperative. The nature of the punch or punches is such and the safety disk is formed of such material and thickness that perforation will only take place when the needle carrying pellet advances with such force as would result from the projectile striking a suitable objective as for instance either a thick or thin armor plate.

In the accompanying drawings, Figure 1 is a longitudinal sectional elevation of one construction of fuse according to this invention showing the needle carrying pellet in its inoperative position. Fig. 2 is a similar view showing the needle carrying pellet and other parts in the positions occu-

pied when the projectile has come into impact with an objective. Fig. 3 is a section on the line 3—3 of Fig. 1. Fig. 4 is a plan of the detonator carrier. Fig. 5 is a vertical section through the upper part of a modified form of fuse also according to this invention, and Fig. 6 is a section on the line 6—6 of Fig. 5.

With reference first to Figs. 1, 2, 3 and 4 the hollow fuse body A is preferably formed cylindrical internally and externally and is screwed into a cap B which forms a shoulder B' approximately about the center of the length of the fuse, the cap around this shoulder being screw-threaded to adapt it to be screwed into the base plug C of the projectile. The cavity in the base plug is of such dimensions that when the fuse is in position an annular space C' is left between the body of the fuse A and the plug C. The bottom of the fuse body A may be integral with it but in the construction shown it is formed as a separate cap A' screwing into and closing the lower end of the fuse body A. The fuse body A contains, so as to be capable of sliding therein, a pellet D which is provided with a needle E of some usual type. Mounted rigidly on one end of the pellet are three punches F, these punches have suitable cutting ends F' and are each reduced in diameter as at F' to allow of the flash passing through the holes in which lie the punches in the manner to be hereinafter described. The detonator G is mounted in a holder or carrier G' conveniently in the form of a cylindrical plug perforated by three holes G² all parallel to the axis of the plug and preferably equidistant from its center as shown in Fig. 4. The detonator G lies in a central recess in the carrier G' this recess communicating through a small passage G³ with another recess G⁴. From this recess G⁴ inclined slots G⁵ lead to the holes G². The holes or passages G² correspond in dimensions and position with the punches F which can slide freely therein. Over the detonator holder G' lies a disk H formed of rolled brass, copper, aluminium or other suitable material and preferably of substantial thickness. The diameter of the disk H is preferably equal to the diameter of the detonator holder G' and thus the disk completely closes in the ends of the guide passages G². The detonator holder G' and disk H lie 110

within the cap B being securely held in place when the latter is screwed to the fuse body A. In the cap B are formed three holes B² which correspond in dimensions and position with the guide passages G² in the detonator carrier and practically constitute continuations of those passages. A radial passage B³ leads from each passage B² to the exterior of the cap B each radial passage B³ conveniently terminating in a cup or recess in which is disposed and suitably secured a powder pellet J. The detonator holder G' is conveniently retained in position so that the passages G² coincide with the passages B² by means of a set screw K which passes through the cap B and enters a slot G⁶ formed in the periphery of the detonator holder.

When the parts are in the position shown in Fig. 1 it will be seen that the ends F' of the punches F bear against those portions of the disk H which cut and block the passages G² B². The pellet D is thus held securely at the inner end of the fuse body with the needle E remote from the detonator G. Any slight movement of the pellet that might be possible and result in chattering is conveniently prevented by a spring L disposed in a recess in the bottom cap A' and bearing against the lower extremity of the pellet. It is apparent that when the parts are in the positions shown in Fig. 1 the passages from the detonator G to the powder pellets J through which passages the flash must pass to ignite these pellets and the projectile charge, are effectively closed by the disk H. Movement of the pellet D cannot take place except under the influence of considerable force by reason of the pellet being rigidly held by the punches F so that the needle is remote from the detonator. In case the detonator should be exploded in some accidental manner there are provided passages A² through the wall of the fuse body A so as to enable the flash to pass from the space in the fuse body between the detonator carrier and the pellet into the annular space C' around the fuse body where the effect of the flash would be harmless.

When the projectile carrying this fuse is discharged and comes into contact with a suitable hard objective the momentum of the pellet D causes the punches F to perforate the disk H and as soon as this perforation takes place the pellet can move forward and on doing so causes the needle E to strike the detonator G. The resulting flash passes through the passage G³ to the recess G⁴, thence through the inclined passages G⁵ to the passages G² B² around the reduced portion F² of the punches F. Thence the flash passes through the radial passages B³ to the powder pellets J which being ignited explode the charge within the projectile. Delay action of the fuse may be

obtained by using a slow burning powder to form the pellets J.

If desired one or more centrifugal bolts of known type may be employed to retain the pellet D in its inoperative position in addition to the retaining action of the punches.

The pellet D is provided with air grooves D' so that its forward motion in the fuse body is not impeded and the ends of a piece of rod D² driven through a transverse hole in the pellet act as feathers in conjunction with grooves formed in the interior of the fuse body A to guide the pellet in its forward movement. This device by preventing rotation of the pellet in the fuse body obviates any wrenching of the punches when the projectile is fired from the gun, the strain which would otherwise be thrown on the punches when the projectile suddenly commences to rotate is thus taken by the feathers.

Figs. 5 and 6 show a modified construction of the cap B in which instead of the short radial passages B³ leading from the holes G⁵ outward to the exterior of the cap longer tangential passages B⁴ are formed in the cap. The ignition pellet J may in some cases be inserted in one of these passages B⁴ instead of in the outer recess.

Although the needle E is shown as being mounted centrally on the pellet D it may be otherwise disposed thereon. The number and position of the punches also may be varied, the guide passages being arranged to correspond. It is desirable however to have the disk H supported in the manner described at or about its center with the punches disposed at some distance from the center so that the disk is supported by solid metal where it receives the principal strain should the detonator through any accidental cause be exploded without perforation of the disk having taken place. This construction is stronger than any arrangement of central punch which necessitates the disk being unsupported at its center.

Although in the construction illustrated the punches are rigidly mounted upon the needle carrying pellet it is to be understood that they need not be actually connected to the pellet but may be separate from it and held in position in any convenient manner so long as the arrangement is such that the pellet can only move forward with the punches.

The punches themselves may be formed in a variety of ways being in some cases hollow or slotted so as to allow the flash to pass when the disk has been perforated. If desired the disk may be cupped or may be provided with a leather or indiarubber washer such as is indicated at M in Fig. 1 for the purpose of insuring a gas tight joint.

It is to be noted that in the fuse accord-

ing to this invention the area of the safety disk exposed to the pressure of the gases from the detonator is small and also that such area is largely shielded before perforation by the presence of the punches which lie against the disk. Further as previously mentioned the safety disk is well supported by the metal of the carrier and the cap and thus the possibility of the safety disk being perforated by the accidental discharge of the detonator and not by the impact of the punches is very remote.

The constructional details may be varied to meet requirements and while the fuse is mainly described and illustrated as being intended for fixing in the base plug of a projectile it may if desired be suitably modified and disposed in the nose of the projectile or at the inner end of the chamber containing the explosive charge.

What I claim as my invention and desire to secure by Letters Patent is:—

1. In a percussion fuse for a projectile the combination of a hollow fuse body, a detonator in said body, a conduit leading from said detonator to an explosive charge, a safety disk closing said conduit, a needle-carrying pellet adapted to move in the hollow fuse body and explode the detonator when the flight of the projectile is arrested by impact with an object and a punch mounted on such needle pellet and adapted to hold it normally away from the detonator and to be carried forward by the pellet to pierce the safety disk as set forth.

2. In a percussion fuse for a projectile the combination of a hollow fuse body, a detonator in said body, a conduit leading from said detonator to an explosive charge, a safety disk closing said conduit, a needle-carrying pellet adapted to move in the hollow fuse body and explode the detonator when the flight of the projectile is arrested by impact with an object and a punch rigidly mounted on such needle pellet and adapted to hold it normally away from the detonator and to be carried forward by the pellet to pierce the safety disk as set forth.

3. In a percussion fuse for a projectile the combination of a hollow fuse body, a cap closing said body and having conduits leading to an explosive charge, a detonator-carrier mounted in said cap and having passages registering with the conduits in the cap, a safety disk normally preventing communication between the conduits in the cap and the passages in the carrier, a detonator mounted in the carrier, a needle-carrying pellet adapted to move in the hollow fuse body and explode the detonator when the flight of the projectile is arrested by impact with an object and punches mounted on the needle pellet guided by the conduits in the carrier and adapted to pierce the safety disk as set forth.

4. In a percussion fuse for a projectile the combination of a hollow fuse body, a cap closing said body and provided with conduits, a detonator carrier having passages registering with the conduits in the cap, a safety disk held between the cap and the detonator carrier and supported by the cap at its central and circumferential portions the only parts unsupported being those which normally close the passages as set forth.

5. In a percussion fuse for a projectile the combination of a hollow fuse body, a cap closing said body and having conduits leading to an explosive charge, a detonator carrier mounted in said cap and having passages registering with the conduits in the cap, a safety disk normally preventing communication between the conduits in the cap and the passages in the carrier, a detonator mounted in the carrier, a needle-carrying pellet adapted to move in the hollow fuse body and explode the detonator when the flight of the projectile is arrested by impact with an object and punches rigidly mounted on the needle pellet guided by the conduits in the carrier and adapted to pierce the safety disk, said punches being reduced in diameter to allow free communication to be established between the passages in the detonator and the conduits in the cap when the disk is pierced as set forth.

6. In a percussion fuse for a projectile the combination of a hollow fuse body, a cap closing said body and provided with conduits, ignition pellets in said conduits, a carrier mounted in said cap and having passages registering with the conduits in the cap, a safety disk normally preventing communication between the conduits in the cap and the passages in the carrier, a detonator mounted in the carrier, a needle-carrying pellet adapted to move in the hollow fuse body and explode the detonator when the flight of the projectile is arrested by impact with an object and punches rigidly mounted on the needle pellet guided by the conduits in the carrier and adapted to pierce the safety disk, said punches being reduced in diameter to allow free communication to be established between the passages in the detonator and the conduits in the cap when the disk is pierced, said punches also serving to hold the needle pellet normally away from the detonator as set forth.

7. In a percussion fuse for a projectile the combination of a hollow fuse body, a cap closing one end of said body and provided with conduits, ignition pellets in said conduits, a carrier mounted in said cap and having passages registering with the conduits in the cap, a safety disk normally preventing communication between the conduits in the cap and the passages in the carrier,

4
a detonator mounted in the carrier, a second cap closing the other end of the fuse body, a needle-carrying pellet guided and adapted to move in the hollow fuse body and explode the detonator when the flight of the projectile is arrested by impact with an object, punches rigidly mounted on the needle pellet guided by the conduits in the carrier and adapted to pierce the safety disk said punches being reduced in diameter to allow free communication to be established between the passages in the detonator and the

conduits in the cap when the disk is pierced, and a spring between the base of the pellet and the cap, said spring tending to keep the ends of the punches in contact with the disk as set forth. 15

In testimony whereof I have signed my name to this specification in the presence of two subscribing witnesses.
